UNITED STATES PATENT OFFICE.

CLARA A. KERN, OF BRIDGEWATER, MICHIGAN.

TOY.

1,368,634.

Specification of Letters Patent. Patented Feb. 15, 1921.

Application filed March 19, 1920. Serial No. 367,079.

To all whom it may concern:

Be it known that I, CLARA A. KERN, a citizen of the United States, residing at Bridgewater, in the county of Washtenaw, 5 State of Michigan, have invented a new and useful Toy; and I do hereby declare the following to be a full, clear, and exact description of the invention, such as will enable others skilled in the art to which it appertains to make and use the same.

The invention relates to toys and has for its object to provide a toy wherein a figure representing a human being or an animal if so desired is pivoted to the upper end of reciprocating members so that said figure may be caused to move as desired as a source of amusement for children.

A further object is to provide a pair of reciprocating members slidable in guides of each other, to the upper ends of which a pivoted arm and a pivoted leg of a figure representing a man are pivoted, said members being so pivoted to the arm and leg of the figure that as the reciprocating members are reciprocated the figure will be caused to dance or bow. The pivoted leg however, being so pivoted, shaped and positioned that as the member to which the arm is pivoted is moved upwardly, said arm and member will come into contact with the front edge of the pivoted leg so that the figure will be raised and the fixed arm in engagement with the reciprocated member to which the pivoted arm is pivoted for holding the figure in an upright position.

With the above and other objects in view the invention resides in the combination and arrangement of parts as hereinafter set forth, shown in the drawing, described and claimed, it being understood that changes in the precise embodiment of the invention may be made within the scope of what is claimed without departing from the spirit of the invention.

In the drawings:

Figure 1 is a side elevation of the toy showing the figure in upright position.

Fig. 2 is a side elevation of the toy showing the figure in a bowed position and ready to be forced upwardly by the engaging of the operating member with the front edge of the pivoted leg of the figure.

Referring to the drawings the numerals 1 and 2 designate reciprocating bars, which bars are slidably mounted in bearing 3 carried by the bar 2 and bearing 4 carried by the bar

1. It will be seen that either bar 1 or 2 may be reciprocated independently or simultaneously if so desired. Pivots secured to the upper end of the bar 2 as at 5 is a pivoted leg 6, which leg is pivoted to a figure 7, as at 8. The leg 9 of the figure is not a pivoted leg and its forward edge is curved as at 10, also the forward edge of the pivoted leg is curved as at 10^a. The curved portion 10^a of the pivoted leg 6 as the bar 1 is moved upwardly from its down position as shown in Fig. 2 to its up position as shown in Fig. 1 engages the curvature 10^a of the pivoted leg so that the figure will be forced to an upright position as shown in Fig. 1. The upper end of the bar 1 is pivoted as at 11 to a pivoted arm 12, which pivoted arm is pivoted as at 13 to the body of the figure 7, thereby allowing the figure to assume the position shown in Fig. 2 on the downward movement of the bar 1. The upward movement of the pivoted arm 12 is limited in its upward movement by the end 14 thereof coming into engagement with the under edge of the permanently fixed arm 15, which arm maintains the figure in its upward position as shown in Fig. 1.

It will be seen that as the end 14 of the slidable member 1 slides along the curved edge 10^a of the leg 6, that the figure 7 will be raised partially to an upright position by means of the pivoted arm 12. The final movement of the arm positions the figure so that the end 14 of the member 1 will engage under the permanently fixed arm 15 and maintain the figure in an upright position as shown in Fig. 1 of the drawing. The movement of the figure may be a limited one and may consist of a rapid reciprocation of the member 1 if so desired.

The invention having been set forth what is claimed as new and useful is:

1. A toy comprising a figure, said figure being provided with a pivoted leg and a pivoted arm pivoted to one side of the body, one arm of the figure being rigid and extending forwardly and being integrally joined to the body, reciprocating members slidable in guides carried by said members, the upper ends of said reciprocating members being pivoted to the pivoted arm and to the pivoted leg and forming means whereby the figure will be caused to move and bow as the reciprocating members are moved in relation to each other, the rigid arm of the figure forming means for engaging the

end of one of the reciprocating members and limiting its movement upwardly.

2. A toy comprising a figure, said figure being provided with a pivoted leg and a pivoted arm pivoted to one side of the figure, one arm of the figure being rigid and extending forwardly and being integrally joined thereto, reciprocating operating bars slidable in guides carried by each other, one of said bars being pivotally connected to the end of the pivoted arm and in a position to contact with the under edge of the fixed arm for limiting the downward movement of the figure and upward movement of said bar, the other bar having its upper end pivotally connected to the pivoted leg of the figure and positioned so that the fixed leg of the

figure when the figure is in down position will be to one side of the pivoted leg so that as the bar which is pivoted to the pivoted arm is forced upwardly it will engage the front edge of the pivoted leg and force the figure to an upright position, said reciprocating bar maintaining the figure in upright position by engagement with the under edge of the fixed arm. 20 25

In testimony whereof I have signed my name to this specification in the presence of two subscribing witnesses.

CLARA A. KERN.
